(57) CLAIM

The ornamental design for a suitcase, as shown and described.

DESCRIPTION

FIG. 1 is a front perspective view of a suitcase of our new design.

FIG. 2 is a front view of the suitcase of our new design.

FIG. 3 is a rear view of the suitcase of our new design.

FIG. 4 is a left view of the suitcase of our new design.

FIG. 5 is a right view of the suitcase of our new design.

FIG. 6 is a bottom view of the suitcase of our new design; and, FIG. 7 is a top view of the suitcase of our new design.

The broken lines illustrate portions of the suitcase and form no part of the claimed design.

1 Claim, 6 Drawing Sheets
